UNITED STATES PATENT OFFICE.

FRED SCHROEDER, OF CLEVELAND, OHIO.

SPARK-PLUG.

1,323,380.

Specification of Letters Patent. Patented Dec. 2, 1919.

Application filed November 1, 1917. Serial No. 199,663.

To all whom it may concern:

Be it known that I, FRED SCHROEDER, a citizen of the United States, and resident of Cleveland, in the county of Cuyahoga and State of Ohio, have invented certain new and useful Improvements in Spark-Plugs, of which I hereby declare the following to be a full, clear, and exact description, such as will enable others skilled in the art to 10 which it appertains to make and use same.

The objects of the invention are to provide a novel form of spark plug in which a more powerful spark can be obtained and in which the insulated core is protected 15 from excessive heat by means of an intermediate body of heat absorbing and distributing material whereby the core will escape irregular expansion and its life will be greatly prolonged.

20 The invention further comprises the combination and arrangement of parts and construction of details hereinafter described, shown in the accompanying drawings and specifically pointed out in the claims.

25 In the accompanying drawings Figure 1 is a side elevation broken away to show the spark producing terminals. Fig. 2 is a longitudinal central section thereof. Fig. 3 is a plan of the lower end thereof. In these 30 views A represents the body of the plug, B the porcelain or other body of insulation or core, C the central electrode, D the clamping sleeve for the porcelain core. E, E, are lock nuts for the electrode.

35 The electrode C is spaced from the porcelain and the annular space partially is filled with the inner lining F formed of mica or other insulating and vitreous material, and between the mica and porcelain 40 is shown a second layer G composed of metal gauze or other porous or spongy metallic substance which absorbs the heat from the electrode, that may pass the layer of mica, and by distributing it evenly to the 45 inner surface of the porcelain prevents irregular expansion and contraction thereof, and, cracking caused thereby.

The metal gauze does not conduct the heat as rapidly as solid metal but absorbs 50 and diffuses it and transmits it more evenly

and slowly to the porcelain. The metal gauze also has a cushion effect to reduce the jam upon the insulation and prevent it from cracking if it should receive a sudden blow from any source. A peculiar formation of 55 sparking terminals is shown in the figures where a central electrode terminates in a circular or hook shaped extremity H which encircles a metal rod I secured transversely of the recess J in the body of the plug. 60

The circular terminal produces at least two heavy sparks, one from the corner L and one from the point K across the gap to the central terminal I. At other points such as Y the terminals are closer together 65 and a spark can be produced from a current of low voltage. The point K of the circular terminal is turned upward and hence prevents the accumulation of oil thereon and consequent deposit of carbon to interfere 70 with a clear spark.

Other advantages are that if one portion of either terminal becomes fouled, the other portions will not fail to produce a spark, at 75 one or more points, and cause the explosion.

The two layers F and G terminate above the lower end of the porcelain and thus are protected from the direct heat of the explosion and engine exhaust. 80

A further advantage lies in the fact that the electrode C is protected by the layers F and G from contact with the hot gases generated in case the projecting lower end at C' should become broken or cracked. 85

This is a great advantage over the ordinary forms of construction. The cavity J is entirely open at the lower end and hence with its walls and the terminals H and I can readily be cleansed if they should become coated with carbon. 90

Having described the invention what I claim as new and desire to secure by Letters Patent is:

1. In a spark plug, a metal body, a central electrode, an inner lining therefor, an outer insulation and an intermediate layer of cushioning and heat diffusing material, substantially as described. 95

2. In a spark plug, a metal body, a cen- 100

tral electrode, an inner insulating lining therefor, an outer insulation, and a layer of spongy metallic substance interposed between said outer and inner insulations.

5 3. In a spark plug, a metal body, a central electrode, an inner insulation therefor, an outer insulation, a layer of spongy metallic substance interposed between said in-

sulations, and means for securing said parts together.

In testimony whereof, I hereunto set my hand this 24th day of October, 1917.

FRED SCHROEDER.

In presence of—

S. W. SANGSTER,
Wm. M. MONROE.
